UNITED STATES PATENT OFFICE.

MARIA PIERI PECCI BALLATI NERLI, OF FLORENCE, ITALY.

WRAPPING FOR HYDROTHERAPEUTIC PURPOSES.

1,000,750.

Specification of Letters Patent. Patented Aug. 15, 1911.

Application filed January 28, 1909. Serial No. 474,849.

To all whom it may concern:

Be it known that I, MARIA PIERI PECCI BALLATI NERLI, a subject of the King of Italy, and resident of Florence, Italy, have 5 invented new and useful Improvements in and Relating to Wrappings for Hydro-therapeutic Purposes, of which the following is a specification.

This invention relates to a wrapper for 10 hydrotherapeutic purposes in which are used in the well known manner several super-posed layers of material adapted to fit the different parts of the body, which are to be wrapped. The ends of the wrapper overlap 15 in a similar manner to the wrappers in Austrian Patent #19004 and German Patent 144,401. The wrapper further has straps or belts running through flaps or longitudinally arranged cords similar to the wrappers 20 of British Patent #16032 of 1898 and Swiss Patent #30651 and also buckles to tighten the straps similarly arranged as in British Patent #658 of 1900.

The novelty of my wrapper consists in the 25 arrangement on the outer side of the wrapper of a number of flaps or longitudinally arranged cords spaced short distances apart, and of straps running through these, there- 30 by giving a wrapper which cannot become displaced. In order to allow each part of the body to move freely and be separately 35 treated each part receives its own properly fitted wrapper, which has on its upper and lower edge as well as on suitably disposed points between the edges, straps running 40 through flaps or cords and which can be tightened by means of buckles or the like. This secures the position of the straps once for all and removes it from the arbitrary 45 will of the patient, while on the other hand, the use of the flaps or cords makes it pos- 50 sible to attach a strap to either edge of the wrapper and also to arrange on suitably situated points between those two straps, other straps running through flaps or cords 55 thereby to provide at the edges, as well as in the middle of the wrapper, the required tightness of fit without the danger of dis- placement of the straps and the consequent 60 loosening of the wrapper. This to a certain extent known use of buckles for wrappers is of special advantage in the present case as it enables the patient to attach, for instance, arm wrappers without help, which is im- 65 possible when bandages are used which must be fastened by knots. The interchangeable

overlapping of ends in the invention secures a close connection of the different layers and has the further advantage of allowing the wrapper to be easily strapped tighter or 60 looser as required. The inner layer is se- cured to the wrapper in the known manner by buttons attached to the edges, but the buttons in the present application are ar- ranged all around in such a manner that 65 they allow a cross-shaped overlapping of the separate layers so that the combination of the mentioned advantages prevents the for- 70 merly unavoidable wrinkling or collapsing of the inner layer, thereby making the use 75 of the wrapper for the patient more pleasant and secure than formerly, and guaranteeing a perfect air tight cover.

The subject matter of the invention is 75 illustrated in the drawing in its possible ap- plication, and in section.

It is self-evident that a wrapper can in- close several parts of the body or the whole body.

The wrappers fitted to the parts of the 80 body consist in the usual manner, as shown in the chest part, of three layers, namely, a moisture absorbing layer 1, a water-proof layer 2, and a protecting and heat-retaining layer 3; the water-proof layer may be dis- 85 pensed with, if desired.

Each layer is exactly fitted to the part of the body it is to cover, and they are con- 90 nected to each other by strings, press-but- tons, or similar devices in such manner that 95 the individual layers overlap at the ends so that, as stated before, the displacement and disagreeable wrinkling of the inner folds or the collapsing of the same is made impos- sible. To secure the wrapper to the part of the body which is to be treated, there is pro- 100 vided in my invention at the upper and lower edge of the wrapper and on suitable points between the upper and lower edges, straps 7, belts, etc. carried through flaps 5 or longitudinally arranged cords closely 105 following one another. The free ends of the straps are secured by buckles in order to fasten the wrapper to the body.

The arrangement of the straps and 105 buckles and the dovetailing and overlap- ping of the several layers, modeled in the form of the body to be covered, allows, firstly, to either tighten or loosen the wrap- 110 per and to fasten it to the body without any possibility of displacement, and further to exclude the air from the part to be treated,

and to produce the retention for an extremely long time of the humid heat, which is of utmost importance in such wrappers, without the danger always present in roll 5 bandages of a slipping or drying of the wrapper. A combination of all these advantages gives a wrapper which forms an independent invention and is not anticipated by the above stated inventions.

10 It is self-evident that the wrapper can, by suitable construction, be used equally well for animals. The outer and inner layer can be made from the same material. The inner layer could possibly consist of a high 15 absorbing vegetable matter such as sponge, or peat, or similar material, or be covered by the same, while the outer layer could be made from cotton, wool, flannel, fur, leather or a similar material.

20 What I claim is:

1. A hydrotherapeutic wrapper consisting of several superimposed layers connected with one another by press buttons and shaped to the part of the body to be covered, 25 the ends of said wrapper overlapping when fastened to the body, the outer surface of the wrapper being provided with a plurality of sets of loops, and a plurality of loops, said bands being provided with 30 buckles to secure the ends thereof together.

2. A hydrotherapeutic packing, consisting of several superimposed layers which are shaped to the part of the body to be em-

braced, the ends of said packing overlapping one another when it is in position, a plurality of loops secured to the outer layer of the packing adjacent each end thereof, and bands slidingly passing through said loops, said bands being free from permanent attachment to said packing, whereby said bands may be moved relatively to said packing, said bands being further provided with buckles for securing the ends of said bands together.

3. A hydrotherapeutic packing, consisting of several superimposed layers which are shaped to the part of the body to be embraced, the ends of said packing overlapping one another when it is in position, a plurality of loops secured to the outer layer of the packing adjacent each end thereof, and bands slidingly passing through said loops, said bands being free from permanent attachment to said packing, whereby said bands may be moved relatively to said packing, said bands being further provided with buckles for securing the ends of the bands together, the inner layer of the packing being detachably connected with the outer layer by means of fastening devices.

In testimony whereof I have signed my name to the foregoing specification in the presence of two subscribing witnesses.
